(57) **CLAIM**

The ornamental design for a paint container, as shown and described.

DESCRIPTION

FIG. 1 is a top perspective view of a paint container, showing my new design.

FIG. 2 is a front elevational view thereof. A rear elevational view is a mirror image of the front elevational view.

FIG. 3 is a top plan view thereof.

FIG. 4 is a left side elevational view thereof. A right side elevational view is identical to the left side elevational view; and,

FIG. 5 is bottom plan view thereof.

The broken lines in the views depict environmental features that form no part of the claimed design.
